UNITED STATES PATENT OFFICE

130,307

DESIGN FOR A COASTER

Todd Harris, Brooklyn, N. Y.

Application August 18, 1941, Serial No. 102,920

Term of patent 3½ years

To all whom it may concern:

Be it known that I, Todd Harris, a citizen of the United States, residing at Brooklyn, in the county of Kings and State of New York, have invented a new, original, and ornamental Design for a Coaster, of which the following is a specification, reference being made to the accompanying drawing, which forms a part thereof.

Fig. 1 is a perspective view of the article, showing my new design;

Fig. 2 is a top plan view of the coaster; and
Fig. 3 is a side elevational view of the coaster.

I claim:

The ornamental design for a coaster, substantially as shown.

TODD HARRIS.
